UNITED STATES PATENT OFFICE.

MAUD HEILMAN, OF LOST HILLS, CALIFORNIA.

INFANT'S STOCKING.

Application filed August 17, 1926. Serial No. 129,694.

My invention is an infant's stocking, adapted to pull over an infant's foot and leg and to be attached to the diaper.

An object of my invention is the construction of a loose fitting stocking which may be called a kicking stocking for infants, intended to be drawn over their feet and legs and to be attached to the diaper so that an infant may exercise and kick 10 without danger of catching cold by having its legs exposed.

A further object of my invention is to form a stocking of woven fabric cut to shape more or less to an infant's leg and foot and with the outer side extending considerably above the inner side so that it will reach well up on the infant's thigh, the lower side extending to the knee or slightly above the knee.

20 My invention is illustrated in the accompanying drawings, in which:

Figure 1 shows an infant wearing stockings according to my invention;

Fig. 2 is an elevation of the stocking 25 looking at the inner side;

Fig. 3 is a section of the stocking on the line 3—3 of Fig. 2 in the direction of the arrows.

The stocking is formed preferably of 30 woven material and has a leg portion 1 and a foot portion 2. Both of these are designed to have a loose fit on an infant's foot and leg. The front seam 3 and the rear seam 4 allow the stocking to be folded flat and the outer side at the top 5 extends considerably 35 above the top 6 of the inner side of the stocking. The upper edge is bound with a tape 7 or the like. The stocking is preferably made inside out and then turned so 40 that the seams are on the inside. The stocking is intended to fasten to the child's diaper indicated by the numeral 8 by means of a safety pin 9 or the like.

45 With a stocking constructed substantially as shown the top edge fits up tight against the diaper on the inside and is drawn up tight on the outside, therefore the infant's leg is not exposed and the child may kick or play with all the freedom of bare legs 50 and feet and not be exposed to the danger of catching cold.

It is obvious that my infant's stocking may be changed in shape or in general construction and if desired could be made of

knitted fabric and shaped closer to the leg 55 and foot than the one illustrated. One of the features, however, is in having one side of the stocking much longer than the other side to allow fastening of same to another garment. 60

My invention may be changed in general construction or in specific details without departing from the spirit thereof as set forth in the description, drawings and claims. 65

In order to supply sufficient strength to the stocking without making it unduly heavy, the front and rear seams 3 and 4 are joined to the binding tape 7 which extends around the top 6 at substantially the 70 level of the infant's knee and around the outside part 5 of the top which extends upwardly over the child's thigh to be fastened to the diaper 8 by the safety pin 9. Therefore the tearing stresses on the upper part 5 75 when the infant kicks and the like are carried by the binding 7 to the front and rear seams 3 and 4 and hence distributed over the stocking.

Having described my invention, what I 80 claim is:

1. An infant's stocking having a leg and a foot portion with front and back seams, the inside of the leg portion at the top being substantially straight across the stocking 85 from seam to seam and the outside of the leg portion extending upwardly from the front and back seams to a considerable height above the top of the inner portion, and a binding on the outside upper extension, said binding joining the front and back seams. 90

2. An infant's stocking having a leg and a foot portion with front and back seams, the inside of the leg portion at the top being 95 substantially straight across the stocking from seam to seam and the outside of the leg portion extending upwardly from the front and back seams to a considerable height above the top of the inner portion, and a binding on the inside top edge of the leg portion, said binding continuing on the edge of the outside extension of the leg portion, said binding being connected to the front and back seams. 100

In testimony whereof I have signed my name to this specification.

MAUD HEILMAN.
